(57) **CLAIM**

The ornamental design for a flatware handle, as shown and described.

DESCRIPTION

FIG. 1 is a front perspective view of a flatware handle showing my new design;

FIG. 2 is a front elevation view of the flatware handle of my new design illustrated in FIG. 1;

FIG. 3 is a right side elevation view of the flatware handle of my new design illustrated in FIG. 1, wherein the left side view is a mirror image thereof; and,

FIG. 4 is a back elevation view of the flatware handle of my new design illustrated in FIG. 1.

The broken lines shown in the drawings are for illustrative purposes only and form no part of the claimed design.
